To all whom it may concern:

Be it known that I, **ALEXANDER MARTINEK**, a citizen of the United States, and resident of Worcester, in the county of Worcester and State of Massachusetts, have invented a new, original, and ornamental Design for Wall Paper, or similar material, of which the following is a specification.

In the accompanying drawing:—

The figure is a surface view of a piece of wallpaper or similar material showing the design. The area within the dot and dash lines indicates one complete unit of the design. Outside of the dot and dash lines frag-

mentary portions of repeat units have been shown arranged around the complete unit so that all units are adjacent each other and in horizontal adjacent lines, and so that the angle of the complete unit designated by letter A corresponds with angle B of a repeat directly below the complete unit.

I claim:—

The ornamental design for wallpaper or similar material as shown and described.

Signed at New York, in the county of New York and State of New York, this 1st day of March, A. D. 1930.
